UNITED STATES PATENT OFFICE.

ERNESTINE P. VAUGHN, OF SOUTHWORTH, WASHINGTON.

HIGH CHAIR FOR CHILDREN.

1,136,300.

Specification of Letters Patent. Patented Apr. 20, 1915.

Application filed March 25, 1914. Serial No. 827,155.

To all whom it may concern:

Be it known that I, ERNESTINE P. VAUGHN, citizen of the United States, residing at Southworth, in the county of Kitsap 5 and State of Washington, have invented a certain new and useful Improvement in High Chairs for Children, of which the following is a specification.

My invention relates to improvements in children's high chairs, and the object of my 10 invention is to provide high chairs each of which shall embody a swingingly movable tray-holder within which may be disposed a removable sanitary tray, preferably made 15 of sheet metal, as aluminum, whereon may be placed dishes of food accessible to the occupant of such chair, such tray-holder to be adapted to be swingingly raised upwardly and backwardly over the back of 20 such chair when its occupant is to be removed therefrom, and further adapted to permit the removal of the tray to clean it as may be required. I accomplish this 25 object by devices illustrated in the accompanying drawings in which—

Figure 1 is a view in side elevation of a child's high chair embodying my invention; Fig. 2 is a view in cross-section of the tray-holder; Fig. 3 is an enlarged view in perspective of such tray-holder; Fig. 4 is an enlarged fragmentary view of a detail of my invention, and Fig. 5 is a view in cross-section of a modified form of my invention. The table of the ordinary child's high chair 35 is usually constructed with an upwardly projecting outer edge that is disposed substantially at right angles to the plane of such table, thus forming a corner from which it is very difficult to remove dirt and 40 foods that may collect therein, such table further being usually constructed of wood that tends to absorb liquid food that may be spilled accidentally thereon and being permanently connected with the chair it 45 cannot be removed for the purpose of washing it.

Referring to the drawings, throughout which like reference numerals indicate like parts, 6 is the frame of an ordinary high 50 chair which is provided with a seat 7 and with a tray-holder 8, said tray-holder 8 being secured at each end to curved side arms 9, 9 that are pivotally connected with the back 10 of the chair to adapt such tray-holder 8 to be swung upwardly over the back of the chair and lowered behind the

chair where it may be allowed to hang when not in use.

The tray-holder 8 is provided with upwardly projecting edge strips 11, 12, 13 and 14 thus to form a shallow receptacle, each of such edge strips 11, 12, 13 and 14 being provided on its inside surface near its top edge with a groove 15 in which the edge 16 of a tray 17 is adapted to rest, as illustrated in Figs. 2 and 4.

In order that the tray 17 easily may be removed from the tray holder 8 I have articulated the end strip 14 by hinges 18 and 19 in such manner that such end strip 14 may 70 swing downwardly into the position shown in Fig. 2, to permit the tray 17 to be drawn outwardly, the edges 16, 16 of the tray 17 sliding in the grooves 15, 15 in the edge strips 11 and 13 and the end strip 14 being 75 automatically raised to its upright position by the pressure of a spring 20 as soon as the tray 17 is withdrawn.

When the tray is to be inserted the end strip 14 may be grasped by the hand and 80 turned downwardly into the position shown in Fig. 2, whereupon the edges 16, 16 of the tray 17 may be inserted in the grooves 15, 15 and the tray 17 moved inwardly into position, the end of the tray 17 adjacent the 85 hinged end strip 14 being of sufficient length when in this position to adapt it to project within the groove 15 in the end strip 14, as more clearly shown in Fig. 4, whereby any pressure on the tray 17 tending to move said 90 tray 17 toward the end strip 14 will cause the edge of said tray 17 to be cramped in the groove 15 of the end strip 14, thus forming a lock to prevent the tray 17 from being removed from the tray-holder 8 unless the 95 end strip 14 is first swung outwardly until the groove 15 of such strip 14 is free from the edge 16 of the tray 17, the spring 20 being sufficiently strong to hold the end strip 14 in an upright position when a pressure is exerted to turn said end strip 14 down.

The tray 17 is preferably constructed of metal, as aluminum, tin and the like, and is formed of a shape that adapts it easily to 105 be cleaned and such tray 17 is adapted to fit snugly in the grooves 15, 15 whereby no food or dirt may be allowed to lodge in said grooves 15, 15 or come in contact with the tray-holder 8 when the tray 17 is in place.

In Fig. 5 I have shown a modified form 110 of my invention wherein a tray-holder 21

that is similar to the tray-holder 8, has the hinged end strip 14 replaced by a slotted end 22 which permits a tray 23 similar to the tray 17 to be inserted therein, such tray 23 being adapted to slide under a cross-bar 24 that is formed by slotting the end 22, and the lower surface of such cross-bar 24 is provided with a peculiarly shaped spring clip 25 that is adapted to prevent the tray 23 from being accidentally displaced on or removed from the tray-holder 21, the clip 25, by its peculiar shape, being adapted to permit the tray easily to be inserted and to prevent such tray from being removed until such clip has been pressed upwardly against the lower surface of the cross-bar 24 as by pressure of one's finger.

Manifestly numerous changes may be made in the shape and form of the various parts of my invention without departing from the spirit of my invention or sacrificing any of its advantages.

What I claim is:

1. A tray-holder for a high chair, comprising upwardly projecting grooved side strips disposed on said tray-holder, a dished

tray having outwardly projecting lateral edges that are adapted to fit in said grooves, and a spring pressed pivoted end strip provided on said tray-holder, said end strip being adapted to be turned downwardly against the tension of the spring to permit said tray to be inserted in said tray-holder.

2. The combination with a high chair, of a tray-holder swingingly hinged to the back of the chair, upstanding side and end walls carried by said tray-holder, a groove formed in the inner face of each of said walls and arranged to provide an endless recess, one of said end walls being hingedly connected to said tray-holder, and a removable dished tray having a peripheral flange to be received in said recess when said hinged end is lowered and be retained in position by said end.

In witness whereof, I, hereunto subscribe my name this fourteenth day of March, A. D., 1914.

ERNESTINE P. VAUGHN.
